United States Patent

Des. 239,776
Patented May 4, 1976

239,776

CIGARETTE LIGHTER

Kenjiro Goto, Tokyo, Japan, assignor to Mansei Kogyo
Kabushiki Kaisha, Kawaguchi, Saitama, Japan

Filed Mar. 24, 1975, Ser. No. 561,554

Term of patent 14 years

Int. Cl. D27—05

U.S. Cl. D27—36

FIG. 1

FIG. 2

FIG. 3

FIG. 4

FIG. 5

FIG. 6

FIG. 1 is a perspective view of a cigarette lighter showing my new design, the top being open;

FIG. 2 is a front end elevational view of the cigarette lighter, the top being closed;

FIG. 3 is a right side elevational view thereof;

FIG. 4 is a rear end elevational view thereof;

FIG. 5 is a top plan view thereof; and

FIG. 6 is a bottom plan view thereof.

I claim:

The ornamental design for a cigarette lighter, substantially as shown and described.
